CAR TRUCK

Edwin W. Webb, Chicago, Ill., assignor to Standard Car Truck Company, Chicago, Ill., a corporation of New Jersey

Application July 5, 1934, Serial No. 733,746

10 Claims. (Cl. 105—206)

This invention relates to car trucks.

It is the general object of the invention to provide novel and improved means of simple and efficient construction for breaking up or minimizing spring harmonics in car trucks.

To this end, the invention consists in the novel parts and novel combinations of parts herein-after defined in the claims and described in the following specification, made in connection with the accompanying drawings, wherein like reference characters refer to the same or similar parts throughout the various views, and, in which,

Fig. 1 is a view in side elevation illustrating portions of a car truck embodying the present invention, certain of the parts being broken away and shown in section;

Fig. 2 is a vertical section taken on the line 2—2 of Fig. 1, as indicated by the arrows;

Fig. 3 is a vertical section taken on the line 3—3 of Fig. 1, as indicated by the arrows; and

Fig. 4 is a horizontal section taken on the line 4—4 of Fig. 1, as indicated by the arrows.

Referring to the drawings, there are illustrated portions of a side frame of a freight car truck including compression member 5, tension member 6 and bolster columns 7 extending between the compression and tension members and defining the sides of a lateral bolster opening 8 within which one end of a bolster 9 works. The tension member 6 below the opening 8 is provided with a widened spring plank seat 10 which projects both inwardly and outwardly beyond other portions of the side frame. A spring plank 11 rests at its end in usual fashion on the spring plank seat 10. A spring plate 12 rests on the end of the spring plank 11 and supported on this plate are a number of inner and outer coiled springs 13, the inner springs being transversely spaced from the outer springs. These coiled springs 40 bear at their upper ends against a plate 14 located below the bolster 9.

The bolster columns 7 below the portions against which the bolster works are forked to provide passages 15 through which a leaf spring 16 extends. This leaf spring extends longitudinally of the side frame midway between the inner and outer coiled springs 13 below the bolster 9. The various leaves of the spring are held in assembled relation by means of a central clip 18 which encircles the leaves and bears against the plate 14, the clip being restrained from movement longitudinally of the side frame by a pair of spaced downwardly projecting lugs 19 carried by the plate 14.

55 The compression member of the side frame for-

wardly and rearwardly of the columns 7 is equipped with downwardly projecting, apertured, spaced, ears 20 within which heavy transversely extending pivot studs 21 are mounted. Hangers 22 depend from these pivot studs and each of these hangers is preferably provided at its upper end with a transverse hub 22a encircling a pivot stud 21 between the ears 20 through which the stud runs and each hanger has a lower rectangular portion 22b, the bottom of which forms a 10 support for one end of the leaf spring 16. The bottoms of the rectangular portions 22b of the hanger are provided with transverse slots 22c within which downturned ends 16a of the lowermost leaf of the leaf spring 16 are received.

It will be seen that the bolster 9 is supported partially by the coiled springs 13 which are in turn supported from the tension member 6 of the side frame and that the bolster 9 is also supported partially by the leaf spring 16 which is in turn supported by the hangers 22 depending from the compression member 5 of the side frame. The stresses and strains imposed on the side frame through its support of the bolster are more evenly distributed than is the case where 25 coiled and leaf springs are supported entirely from the tension member alone. As the hangers 22 are free to swing, the leaf spring 16 will be flexibly supported at its ends. The coiled and leaf springs mutually cooperate to sustain the 30 truck bolster and its load and the coiled springs dampen the natural harmonic action of the leaf spring and the leaf spring dampens the natural 35 harmonic action of the coiled springs. This eliminates or materially reduces vibrations in the truck.

It will be understood that trucks embodying the present invention may be equipped with lateral motion devices permitting lateral motion 40 of the bolster, if so desired. These lateral motion devices may be interposed in the usual manner between the lower side of the bolster and the various springs 13 and 16.

It will, of course, be understood that various 45 changes may be made in the form, details, arrangement and proportions of the various parts without departing from the scope of the present invention.

What is claimed is:—

1. In a car truck, a side frame having compression and tension members and bolster columns extending between the said members and defining a lateral opening, a bolster working within said opening, a spring supported by said tension member and assisting to support said bolster and 55

a spring supported beneath said bolster by said compression member and assisting to support said bolster.

2. The structure defined in claim 1, the first mentioned spring being of one type and the last mentioned spring being of a different type.

3. In a car truck, a side frame including compression and tension members and columns running between said members and defining a lateral bolster opening, a bolster working within said opening, coiled springs supported from said tension member and in turn assisting in supporting said bolster and a bar spring supported from said compression member below said bolster and in turn assisting in supporting said bolster.

4. In a car truck, a side frame having compression and tension members and bolster columns extending between the said members and defining a lateral opening, a bolster working within said opening, coiled springs supported by said tension member and assisting to support said bolster and a bar spring supported by said compression member, extending longitudinally of the side frame across said bolster below the same and also assisting to support the bolster.

5. In a car truck, a side frame having compression and tension members and columns extending between said members and defining a lateral bolster opening, a bolster working within said opening, a spring supported by said tension member and in turn assisting to support said bolster, hangers depending from said compression member and a spring supported by said hangers below the bolster and in turn assisting to support said bolster.

6. In a car truck, a side frame having compression and tension members, columns extending between said members and defining a lateral bolster opening, a bolster working within said opening, springs supported from said tension member and in turn assisting to support said bolster, hangers pivotally connected to and depending from said compression member and a bar spring supported by said hangers below the bolster and in turn assisting in supporting said bolster.

7. In a car truck, a side frame having a lateral

opening, a bolster having an end disposed within said opening, coiled springs supported from said side frame and assisting in supporting the end of said bolster, a leaf spring disposed below said bolster and assisting in supporting the same, said leaf spring extending longitudinally of the side frame and projecting across said opening and hangers pivotally mounted on upper portions of the side frame and projecting downwardly therefrom and upon which the ends of said leaf spring are supported.

8. In a car truck, a side frame having tension and compression members and bolster columns extending between said members and defining a lateral opening, a bolster having an end working within said lateral opening, coiled springs supported on said tension member and in turn partially supporting said bolster, a bar spring extending longitudinally of the side frame below the bolster and in turn partially supporting said bolster, said columns having spring passages through which said bar spring extends and hangers pivotally mounted on said compression member and depending therefrom and upon which the ends of which said bar spring rest.

9. The structure defined in claim 8, said bar spring having down turned ends and said hangers having slots in their lower portions receiving said downturned ends.

10. In a car truck, a side frame having compression and tension members and columns extending between said members and defining a lateral bolster opening, said tension member below said opening having inner and outer projections, a bolster working within said opening, inner and outer coiled springs supported respectively on said inner and outer projections and in turn assisting to support said bolster, said inner and outer springs being spaced from each other transversely of the side frame, hangers carried by said compression member and depending downwardly therefrom and a bar spring below said bolster extending longitudinally of said side frame between said inner and outer springs, supported by said hangers and in turn assisting to support said bolster.

EDWIN W. WEBB.
